[57] CLAIM

The ornamental design for a facsimile, as shown and described.

DESCRIPTION

FIG. 1 is a top, front and right side perspective view of a facsimile showing my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof, with the sheet support in a raised position and the hand set inverted; and

FIG. 8 is an enlarged fragmentary top and left side perspective view thereof, with the hand set inverted.

FIG. 1

FIG. 2
